US00D988491S

(12) **United States Design Patent** (10) **Patent No.:** **US D988,491 S**
(45) **Date of Patent:** **** Jun. 6, 2023**

(54) **AIR FRESHENER DEVICE**(71) Applicant: **The Procter & Gamble Company**,
Cincinnati, OH (US)(72) Inventor: **Richard Lee Lane**, Cincinnati, OH
(US)(73) Assignee: **The Procter & Gamble Company**,
Cincinnati, OH (US)(**) Term: **15 Years**(21) Appl. No.: **29/707,597**(22) Filed: **Sep. 30, 2019****Related U.S. Application Data**(63) Continuation of application No. 15/582,841, filed on
May 1, 2017, now Pat. No. 10,471,168.(60) Provisional application No. 62/330,871, filed on May
3, 2016.(51) **LOC (14) Cl. .... 23-04**(52) **U.S. Cl.**USPC ..... **D23/366**(58) **Field of Classification Search**USPC D23/355–366, 352, 369, 332, 333, 335,

(Continued)*Primary Examiner* — David G Muller*(74) Attorney, Agent, or Firm* — George H. Leal; Abbey
Alicia Lopez**CLAIM**The ornamental design for an air freshener device, as shown
and described.**DESCRIPTION**FIG. 1 is an isometric view of a second embodiment of an
air freshener device having a front housing, a translucent or
transparent dome, and a rear housing;FIG. 2 is an isometric view of the air freshener device of
FIG. 1;FIG. 3 is a front view of the air freshener device of FIG. 1;
FIG. 4 is a back view of the air freshener device of FIG. 1;
FIG. 5 is a right view of the air freshener device of FIG. 1;
FIG. 6 is a left view of the air freshener device of FIG. 1;
FIG. 7 is a top view of the air freshener device of FIG. 1;
and,FIG. 8 is a bottom view of the air freshener device of FIG.
1.The broken lines in the figures show portions of the air
freshener device that form no part of the claimed design.**1 Claim, 8 Drawing Sheets**(56)
